UNITED STATES PATENT OFFICE.

JAMES BURKE, OF ERIE, PENNSYLVANIA, ASSIGNOR TO BURKE ELECTRIC COMPANY,
A CORPORATION OF PENNSYLVANIA.

DYNAMO-ELECTRIC MACHINE.

1,361,136.

Specification of Letters Patent. Patented Dec. 7, 1920.

Application filed February 6, 1917. Serial No. 146,884.

To all whom it may concern:

Be it known that I, JAMES BURKE, a citizen of the United States, residing at Erie, in the county of Erie and State of Pennsylvania, have invented certain new and useful Improvements in Dynamo-Electric Machines, of which the following is a specification.

My invention relates to an improved method and form of construction of dynamo electric machines which is especially applicable to comparatively small sizes of motors, generators and the like.

The main objects are to simplify the method of construction and reduce the amount of labor necessary and also reduce the cost of material while producing a strong and durable construction with reduction of size and weight of the machine.

My invention will be understood from the following description and accompanying drawings, in which—

Figure 1 is a cross section illustrating one stage of manufacture; Fig. 2 is an end view 25 of Fig. 1; Fig. 3 is a cross section of a further stage of manufacture; Fig. 4 is an end view of the construction illustrated in Fig. 3 with the auxiliary clamping and shaping means removed; Fig. 5 is a plan showing the outline of the sheet metal base; Fig. 6 is a plan view of the base after being 30 bent to its final shape. Fig. 7 is an end view of Fig. 6; Fig. 8 is a side view of Fig. 6; Fig. 9 is a plan view of the completed 35 machine, and Fig. 10 is an end view thereof.

Instead of providing the usual heavy cast iron frame which is costly in material and labor, I utilize sheet metal of commercial gage and shape the same to fulfil the function of supporting and protecting the operative parts of the machine. In accordance 40 with my invention the main frame is made in its preferred form from a rectangular sheet of steel, the size of the rectangle being cut to that suitable to the particular dynamo 45 desired. The rectangular sheet is then rolled to an approximately circular shape bringing the two ends of the rectangular sheet near together. Any suitable holding or clamping 50 means is then used for holding the sheet in its final form, such as the two encircling rings 11—11, the size of which are of proper standard for the size of the dynamo desired. The size is such as to bring the two edges 55 of the sheet 12 together forming a joint as

at 13. An end ring 14 is then placed within the circular frame and fixed in place at the proper distance from one end of the circular frame, preferably by arc welding at spots displaced around the periphery as indicated at 15. The welding of this end ring in place serves to retain the circular sheet metal frame in proper shape. In some instances it may be desirable to weld together the edges of the circular frame along 60 the joint 13, but ordinarily this is unnecessary.

The stator laminæ 16 may now be assembled within the housing or may be separately assembled or built up on positioning 70 pins or other form, and forced within the circular frame against the end ring 14. Another ring 17 is applied on the opposite end of the laminæ. The laminæ are then forced and held together in any suitable way until 75 the ring 17 is located at the proper predetermined distance from its end of the circular frame and is then arc welded in spots 15' to the circular frame, in the same manner as the end ring 14. As one method of clamping 80 the laminæ together so as to permit the ring 17 to be brought to its intended position, two flanges or spiders 18 are shown, one on each side of the laminæ, and a bolt 19 and nut 20 for compressing the laminæ 85 to any desired amount. After the ring 17 is welded in position, the clamping means and the rings 11 may be removed. This completes the stator frame and housing, no machine work being necessary, except truing 90 up the edges of the housing by placing the parts in a mandrel so that the edges of the housing will be at right angles to the axis of the rotor.

The base or foot of the machine is also 95 preferably formed of a single piece of sheet metal. A sheet of steel is first punched to the shape shown in Fig. 5 with a central opening and diagonal cuts as shown at 21 and with end projections 22 and slots 23. 100 The parts 24 between the cuts 21 are next bent upwardly so as to form projecting lips as shown in Figs. 6 and 7. The side portions 25 of the sheet metal are then bent downwardly on the horizontal dotted lines 105 shown in Fig. 5 and the end projections 22 are bent downwardly on the line of the vertical dotted lines. This gives the final form of the base or foot as shown in Figs. 6, 7 and 8, the slot 23 serving to provide means 110

for bolting the machine in any desired location. The side portions of the foot have a circular recess as shown in Fig. 8 which is of a radius adapted to fit around the circular sheet metal housing of the dynamo; and the lips 24 are also of such length as to reach the circular housing of the machine when placed in position on the base. The base is now welded to the housing by arc welds 10 along the upper edges of the lips 24 and along the line of contact with the side portions of the base.

The shape or form of the foot or base may be made as desired to suit the particular use to which the machine is to be put, without the necessity of altering the housing which is another advantage over cast frames which require a separate pattern for the housing and base for each different form of base even with the same size of machine or housing.

The completion of the dynamo by the provision of stator windings and of the rotor is made in the usual manner, the end frames 25 26, 26' for supporting the rotor shaft, brushes, etc., being fitted to the ends of the sheet metal housing and bolted together or in place in any desired manner, such as by through bolts passing through holes in the 30 stator laminæ.

Although I have described one embodiment of my invention, it will be understood that various modifications may be made without departing from the scope thereof.

35 I claim:

1. In a dynamo, the combination of a cylindrical housing consisting of a single rectangular sheet of metal bent to have a single butt joint, and a ring secured therein and 40 serving both to hold the said housing in shape and as an abutment to secure the stator laminæ.

2. In a dynamo, the combination of a sheet metal housing consisting of a single 45 sheet of metal having a single longitudinal butt joint, a retaining ring for the stator laminæ secured to said housing, and a second retaining ring for the stator laminæ secured to said housing.

50 3. In a dynamo, the combination of a cylindrical sheet metal housing, a retaining ring for the stator laminæ within said housing, said ring being autogeneously joined to said housing, a second retaining ring for 55 the stator laminæ for retaining said laminæ in position, said last mentioned ring being autogeneously joined to said housing, and end frames for supporting the rotor shaft positioned on the ends of said cylindrical 60 housing.

4. In a dynamo, the combination of a housing, and a sheet metal base secured to said housing, said sheet metal base consisting of a plate having an opening there- 65 through and having its inner edges bent

up to form a seat and its outer edges bent down to form a box like support.

5. In a dynamo, the combination of a housing, and a sheet metal base secured to said housing, said sheet metal base comprising 70 a plate having an opening therethrough and its inner edges bent up to form a seat.

6. In a dynamo, the combination of a housing, and a sheet metal base secured to said housing, said sheet metal base consisting of 75 a plate having an opening therethrough with its inner edges bent to conform to the outline of said housing and secured thereto.

7. In a dynamo, the combination of a 80 housing, and a sheet metal base secured to said housing, said sheet metal base being formed of an integral sheet having sides and ends bent at right angles and also having an opening therethrough with its edges 85 shaped to conform to the outline of the housing and secured to said housing.

8. The method of making a stator element for dynamos which consists in bending a sheet of metal to form the housing, 90 welding a ring within said housing, meanwhile holding the housing in shape by means of a temporary ring slipped around it, placing stator laminæ within said housing against said ring, and welding another 95 ring within said housing on the other side of said laminæ from said first ring, and then removing the temporary ring.

9. The method of making a stator element for dynamos which consists in bending a single rectangular sheet of metal in cylindrical form with its ends butted together to form the housing, holding the housing in shape by means of a temporary ring slipped around it, securing an abutment ring within said housing, placing stator laminæ within said housing against 100 said abutment ring, securing another ring within said housing on the other side of said laminæ, said rings within the housing 105 serving to hold the shape of the housing, and then removing the temporary outer ring.

10. In a dynamo, a cylindrical housing of a single piece of metal with a single longitudinal butt joint, a ring therein, said housing and ring being autogeneously joined together, and stator laminæ abutting 115 against said ring.

11. In a dynamo, the combination of a 120 cylindrical housing and a sheet metal base to receive the same, said base consisting of a sheet metal plate having an opening therethrough, the edges of said opening being turned up to make a seat conforming to the 125 cylindrical contour of the housing and said edges being autogeneously joined to said housing.

JAMES BURKE.
